No. 37,039.

Patented July 12, 1904.

UNITED STATES PATENT OFFICE.

HENDERSON M. POWERS, OF LANCASTER, PENNSYLVANIA.

DESIGN FOR A SNAP-HOOK AND TRACE-END RETAINER.

SPECIFICATION forming part of Design No. 37,039, dated July 12, 1904.

Application filed January 7, 1904. Serial No. 188,150. Term of patent 7 years.

To all whom it may concern:

Be it known that I, HENDERSON M. POWERS, a citizen of the United States, residing at Lancaster, in the county of Lancaster and State of Pennsylvania, have invented a new, original, and ornamental Design for a Snap-Hook and Trace-End Retainer, of which the following is a specification, reference being had to the accompanying drawings, in which—

Figure 1 is a side elevation, Fig. 2 a front

end view, and Fig. 3 a rear end view, of a snap-hook, showing my new design.

What I claim is—

The ornamental design for a snap-hook and trace-end retainer, as shown.

HENDERSON M. POWERS.
